UNITED STATES PATENT OFFICE.

JOSEPH H. MURRAY, OF HOMER, GEORGIA.

FORGE.

1,261,843.

Specification of Letters Patent.

Patented Apr. 9, 1918.

Application filed November 2, 1916. Serial No. 129,166.

To all whom it may concern:

Be it known that I, JOSEPH H. MURRAY, a citizen of the United States, residing at Homer, in the county of Banks, State of Georgia, have invented a new and useful Forge; and I do hereby declare the following to be a full, clear, and exact description of the invention, such as will enable others skilled in the art to which it appertains to make and use the same.

This invention relates to an improved forge, and one of the objects of the invention is to provide means whereby a blast of air may be forced into the forge, to cause the fire to burn.

Another feature of the invention is to provide a slide plate having apertures to co-operate with the apertures of the tapering outlet of the blower, to regulate the blast of air to the forge.

Another feature of the invention is the provision of a deflector for deflecting the blast of air toward the bottom of the fire of the forge, in order to cover the full area of the fire.

In practical fields, the details of construction may necessitate alterations falling within the scope of what is claimed.

The invention comprises further features and combination of parts, as hereinafter set forth, shown in the drawings, and claimed.

In the drawings:—

Figure 1 is a view in side elevation and partly in section of a portion of the forge pot, showing the motor driven blower applied.

Fig. 2 is a sectional view through the forge pot and through the motor for driving the blower, which is shown partly in elevation.

Fig. 3 is a sectional view on line 3—3 of Fig. 1.

Fig. 4, is a detail view in side elevation showing the spring tensioned gear of the spring motor.

Fig. 5 is a detail view of the spring dog for engaging a ratchet wheel on the shaft of the spring tensioned gear for preventing the spring of said gear from unwinding when once wound.

Fig. 6 is a detail sectional view through the end of the arm or lever 13 of the rod 11, showing the spring tensioned pin 14.

Referring more especially to the drawings, 1 designates the casing of the blower, in bearings of which a shaft 2 is mounted.

Mounted upon the shaft 2 is the hub 3 of the wheel 4, by the operation of which wheel, a substantially continuous blast of air is generated and forced through the tapering part 5 of the blower casing. This tapering part 5 of the blower casing extends through the wall 6 of the forge pot, and has an apertured or perforated end wall 7, with which the apertures 8 of the slide 9 coöperate, in order to regulate the amount of air discharged into the forge pot. The slide 9 is mounted in the guides 10.

It is to be observed that by adjusting the slide in one direction or the other, the apertures 8 of the slide can be made to entirely register or partially register with the apertures in the end wall 7, in order to regulate the discharge of the blast. Mounted in suitable bearings on the wall of the forge pot 75 is a rock shaft 11, on which a deflector 12 is carried. This deflector is curved so as to extend down over the apertured slide. When the rod 11 is adjusted to throw the deflector down, the blast of air will be deflected and caused to spread over the whole bottom of the fire of the forge. Should the deflector be moved to extend upwardly, by rocking the rod 11, the blast of air will extend more through the top of the fire of the forge. One 80 end of the rod 11 has an arm 13, in an end of which a spring tensioned pin 14 is mounted, to engage any one of the depressions, 15, to hold the shaft or rod 11 in different adjusted positions.

The shaft 2 is mounted in suitable bearings 16 and 17 of the casing 1, one side of which is provided with a large opening 18, through which air is drawn into the casing 1 as the wheel 4 rotates. Extending from the bearing 17 are arms 19, which connect to the casing 1, thereby connecting the bearing 17 to said casing. A collar 20 is pinned on one end of the shaft 2 to prevent axial movement of said shaft.

Formed integral with the casing 1 is a spring motor casing 21, in suitable bearings of which the shafts 22, 23, 24, 25 and 26 are mounted. The shafts 22 to 25, inclusive, are provided with gears 27 to 34, inclusive, which mesh, as shown in Fig. 3, and are keyed to said shafts. The gear 27 meshes with a gear 35 on the shaft 2. Loose upon the shaft 26 is a gear 36, which meshes with the gear 33 of the shaft 25. Integrally 110 formed on one side of the gear 36 is an annular flange 37 forming a casing for the

spring 38, one end of which is secured at 39 to the shaft 26, whereas the other end is secured at 40 to the flange 37. The shaft 26 has a ratchet 41 keyed thereto, as shown in Fig. 5, and pivoted at 42 to one side of the casing 21 is a pawl or dog 43, which is designed to engage the teeth of the ratchet 41, to prevent the retrograde movement of the shaft 26, in other words, prevent the spring 10 38 from unwinding after once having been wound. One end of the shaft 26 has a crank 44 secured to it as at 45, whereby the shaft 26 may be rotated for winding the spring. Secured by suitable pins 46 to the shaft 26 15 are collars 47, between which the collar 48 of the pawl or dog 49 is mounted, so the pawl or dog 49 will engage the teeth of the gear 34, thereby preventing the chain of gears from operating under the action of 20 the spring 38. The pawl 49 has a laterally extending pin 50 extending through a slot 51 of one of the side walls of the casing 21, and by grasping this pin, the pawl may be thrown out of engagement with the teeth of 25 the gear 34, thereby leaving the gears free to move or rotate under the tension or the action of the spring 38, thereby imparting movement to the blower, which will force the blast of air through the tapering part 5 of 30 the casing 1. The casing 21 has a suitable cover 53, which may be removed to permit access to the interior of the casing 21, for oiling and repairing the gears. The slide has an extension rod 52 extending through the 35 wall of the forge and provided with a handle

54, whereby the slide may be moved or adjusted.

The invention having been set forth, what is claimed as new and useful, is:—

1. In a forge, a blower having a tapering part extending through the wall of the forge and having a discharge passage, the end of said tapered part having perforations, the wall of the forge having guides at the top and bottom of said end, a slide mounted in the guides and having perforations, and adapted to move on and against said end, whereby the perforations of the slide may cooperate with the perforations of the end for regulating the blast of air into the forge, 45 and a deflector pivoted in the wall of the forge for deflecting the blast of air as it passes through the perforations of the end and the slide.

2. In a forge, a blower having a tapering discharge nozzle extending through the wall of the forge and provided with means for regulating the blast of air into the forge, a deflector pivoted in the wall of the forge and adjustable to extend down over said 60 means, whereby the blast of air may be deflected downwardly.

In testimony whereof I have signed my name to this specification in the presence of three subscribing witnesses.

JOSEPH H. MURRAY.
